**DISPLAY APPARATUS HAVING LOCK
FUNCTION AND DISPLAY DRIVING
CIRCUIT THEREOF**

**CROSS-REFERENCE TO RELATED
APPLICATIONS**

This application is a continuation of U.S. patent application Ser. No. 18/210,101, filed on Jun. 15, 2023 (now U.S. Pat. No. 12,062,319, issued on Aug. 13, 2024), which is a continuation of U.S. patent application Ser. No. 17/820,862, filed on Aug. 18, 2022, (now U.S. Pat. No. 11,783,754, issued on Oct. 10, 2023), which claims the priority of Korean Patent Application No. 10-2021-0134886 filed on Oct. 12, 2021, which are hereby incorporated by reference in their entirety.

BACKGROUND

Field of the Disclosure

The present disclosure relates to a display apparatus, and more particularly, to a display apparatus having a lock function for transferring a lock signal through display driving circuits and feeding the lock signal back to a timing controller and the display driving circuit thereof.

Description of the Background

In general, a display apparatus is configured such that display data is transmitted from a timing controller to a display driving circuit, the display driving circuit outputs a source signal corresponding to the display data, and a display panel displays a screen in response to the source signal.

The display data transmitted from the timing controller to the display driving circuit is composed of a packet. The display data may include data corresponding to information for display and a clock for driving the data.

The display driving circuit may recover the data and the clock from the display data, may perform a data processing process by using the recovered clock, and as a result, may output the source signal.

When an error occurs in the clock, there is a difficulty in recovering and processing the data normally. The display driving circuit is configured to define a state of the clock as a lock state when the state of the clock is normal, define a state of the clock as an unlock state when the state of the clock is abnormal, and generate and output a lock signal for indicating a state of the clock.

The lock state may be periodically checked by the timing controller. To this end, the timing controller may provide the lock signal to the display driving circuit. The display driving circuit may provide the timing controller with a feedback lock signal, that is, a combination of the lock signal and an internal lock signal. The timing controller may check a lock state of the display driving circuit in response to the feedback lock signal.

The number of constructed display driving circuits may be determined depending on a size and resolution of a display panel.

If a plurality of display driving circuits is constructed, a lock signal may be provided to the plurality of display driving circuits by using a pull-up method using one transmission line or a cascade method of transferring a lock signal through the display driving circuits.

2

In the case of the pull-up method, it is difficult to check a lock state of each of the display driving circuits.

Accordingly, the lock signal may be transferred using the cascade method to check the lock state of each of the display driving circuits.

In general, the timing controller and the display driving circuit may be configured to use voltages having different levels. For example, the timing controller may use a power source of 1.8 V for input and output, and the display driving circuit may use a power source of 3.3 V for input and output.

The display driving circuits and the timing controller have a difficulty in sharing a lock signal because they use heterogeneous power sources as described above. That is, a compatibility problem may occur between the display driving circuit and the timing controller.

The above information disclosed in this Background section is only for enhancement of understanding of the background of the described technology and therefore it may contain information that does not form prior art that is already known to a person of ordinary skill in the art.

SUMMARY

Accordingly, the present disclosure is directed to a display apparatus having a lock function and the display driving circuit thereof that substantially obviate one or more of problems due to limitations and disadvantages described above.

More specifically, the present disclosure is to provide a display device guaranteeing compatibility for sharing a lock signal between display driving circuits and a timing controller using heterogeneous power sources.

Additional features and advantages of the disclosure will be set forth in the description which follows and in part will be apparent from the description, or may be learned by practice of the disclosure. Other advantages of the present disclosure will be realized and attained by the structure particularly pointed out in the written description and claims hereof as well as the appended drawings.

To achieve these and other advantages and in accordance with the present disclosure, as embodied and broadly described, a display driving circuit having a lock function includes a comparison unit configured to receive a transfer lock signal and output a comparison signal obtained by comparing the transfer lock signal and an internal lock signal obtained by determining a state of an internal recovery clock, and an output circuit including an internal output pull-up circuit and configured to generate a feedback lock signal having a level corresponding to a level of the comparison signal through the internal output pull-up circuit and to output the feedback lock signal to a lock signal transmission line to which an external power source is applied.

In another aspect of the present disclosure, a display driving circuit having a lock function includes an input circuit including an internal input pull-up circuit and configured to receive and transfer a forwarding lock signal through a lock signal transmission line to which an external power source is applied through the internal input pull-up circuit, a comparison unit configured to output a comparison signal obtained by comparing the forwarding lock signal transferred through the input circuit and an internal lock signal obtained by determining a state of an internal recovery clock, and an output circuit configured to generate a transfer lock signal having a level corresponding to a level of the comparison signal and output the transfer lock signal. The input circuit may transfer the forwarding lock signal to the comparison unit through the internal input pull-up circuit

using an internal power source having a level different from a level of the external power source.

In a further aspect of the present disclosure, a display apparatus having a lock function includes a timing controller configured to output a forwarding lock signal through a first lock signal transmission line and receive a feedback lock signal through a second lock signal transmission line, and a plurality of display driving circuits including a first display driving circuit for receiving the forwarding lock signal through the first lock signal transmission line and a second display driving circuit for outputting the feedback lock signal through the second lock signal transmission line, and configured to transfer lock signals in a cascade way, respectively. An external power source may be applied to the first lock signal transmission line and the second lock signal transmission line. The first display driving circuit may receive the forwarding lock signal through an internal input pull-up circuit. The second display driving circuit may output the feedback lock signal through an internal output pull-up circuit.

The present disclosure may buffer a voltage difference between heterogeneous power sources by pull-up when a forwarding lock signal is provided from the timing controller to the display driving circuit or a feedback lock signal is provided from the display driving circuit to the timing controller.

Accordingly, the present disclosure has an effect in that it may secure compatibility for sharing a lock signal between the display driving circuits and the timing controller using heterogeneous power sources.

It is to be understood that both the foregoing general description and the following detailed description are exemplary and explanatory and are intended to provide further explanation of the disclosure as claimed.

BRIEF DESCRIPTION OF THE DRAWINGS

The accompanying drawings, which are included to provide a further understanding of the disclosure and are incorporated in and constitute a part of the disclosure, illustrate aspects of the disclosure and together with the description serve to explain the principle of the disclosure.

In the drawings:

FIG. 1 is a block diagram illustrating a display apparatus according to an aspect of the present disclosure; and

FIG. 2 is a circuit diagram illustrating a display driving circuit according to an aspect of the present disclosure, which is illustrated in FIG. 1.

DETAILED DESCRIPTION

To drive a display panel for displaying a screen, a display apparatus may include a timing controller and drivers.

Referring to FIG. 1, a timing controller 10 and display driving circuits 20, 22 and 24 are illustrated.

The timing controller 10 provides the display driving circuits 20, 22 and 24 with display data DL1, DL2 and DLn (wherein n is a natural number greater than 2), respectively. To this end, data transmission lines 16, 17 and 18 are configured between the timing controller 10 and the display driving circuits 20, 22 and 24.

More specifically, the display data DL1 is provided to the display driving circuit 20 through the data transmission line 16. The data display DL2 is provided to the display driving circuit 22 through the data transmission line 17. The display data DLn is provided to the display driving circuit 24 through the data transmission line 18. Each of the data

transmission lines 16, 17 and 18 may be configured to include m channels. In this case, m means a natural number greater than 2.

Furthermore, the timing controller 10 is configured to output a forwarding lock signal LKF to the display driving circuit 20 through a lock signal transmission line 12 and to receive a feedback lock signal LKL of the display driving circuit 24 through a lock signal transmission line 14.

The lock signal transmission line 12 is configured between the timing controller 10 and the display driving circuit 20. The lock signal transmission line 14 is configured between the timing controller 10 and the display driving circuit 24. The lock signal transmission lines 12 and 14 may be configured as a single line.

The timing controller 10 may use a power source that provides a voltage of 1.8 V for operation, and input and output, for example. The power source that provides a voltage of 1.8 V may be understood as an external power source on the part of the display driving circuits 20, 22 and 24. Accordingly, the power source that provides the voltage of 1.8 V for an operation and input and output of the timing controller 10 may be defined as an external power source T_VDD.

In FIG. 1, the external power source T_VDD is illustrated as being applied to the lock signal transmission line 12 through which the timing controller 10 outputs the forwarding lock signal LKF and the lock signal transmission line 14 through which the timing controller 10 receives the feedback lock signal LKL. Through the construction, the forwarding lock signal LKF and the feedback lock signal LKL may be transferred using the external power source T_VDD.

The display driving circuits 20, 22 and 24 are configured to transfer lock signals by using the cascade method.

More specifically, the display driving circuit 20 is configured to receive the forwarding lock signal LKF of the timing controller 10 through the lock signal transmission line 12 and to provide a transfer lock signal LK1 to the display driving circuit 22 through a lock signal transmission line 21. Furthermore, the display driving circuit 24 is configured to receive a transfer lock signal LKn of a previous display driving circuit (not illustrated) through a lock signal transmission line 25 and to provide the feedback lock signal LKL to the timing controller 10 through the lock signal transmission line 14. The display driving circuits 20, 22 and said previous display driving circuit are configured to sequentially transfer the transfer lock signals LK1, LK2 and LKn through the lock signal transmission lines 21, 23 and 25, respectively.

The display driving circuits 20, 22 and 24 may use an internal power source that provides a voltage of 3.3 V for operation, and input and output, for example. The internal power source may be defined as SD_VDD.

The transfer lock signals LK1, LK2 and LKn between the display driving circuits 20, 22 and 24 are transferred through the lock signal transmission lines 21, 23 and 25. The internal power source SD_VDD may be understood to be used in the transfer of the transfer lock signals LK1, LK2 and LKn through the lock signal transmission lines 21, 23 and 25.

In the construction, the external power source T_VDD is applied to the lock signal transmission line 12 for the transmission of the forwarding lock signal LKF. That is, for example, a voltage of 1.8 V is applied to the lock signal transmission line 12 for the transmission of the forwarding lock signal LKF. However, the display driving circuit 20 is configured to use the internal power source SD_VDD for an internal operation. That is, for example, a voltage of 3.3 V

is used to receive the forwarding lock signal LKF transmitted through the lock signal transmission line 12.

In an aspect of the present disclosure, the display driving circuit 20 is configured to include an internal input pull-up circuit to secure compatibility in an environment in which the timing controller 10 and the display driving circuit 20 use heterogeneous voltages as described above. As a result, the display driving circuit 20 may receive the forwarding lock signal LKF through the internal input pull-up circuit using the internal power source SD_VDD having a level different from a level of the external power source T_VDD.

Furthermore, the external power source T_VDD is applied to the lock signal transmission line 14 for the transmission of the feedback lock signal LKL.

In an aspect of the present disclosure, the display driving circuit 24 is configured to include an internal output pull-up circuit to secure compatibility in an environment in which the timing controller 10 and the display driving circuit 24 use heterogeneous voltages as described above. As a result, the display driving circuit 24 may output the feedback lock signal LKL through the internal output pull-up circuit using the internal power source SD_VDD having a level different from a level of the external power source T_VDD.

The constructions of the display driving circuits 20, 22 and 24 are described with reference to FIG. 2. The display driving circuits 20, 22 and 24 may have the same construction, and thus constructions and operations of the display driving circuits 20, 22 and 24 may be understood based on the description of FIG. 2.

First, a case where the aspect of FIG. 2 is used as the display driving circuit 20 is described. This case corresponds to a construction for receiving the forwarding lock signal LKF through an internal input pull-up circuit using the internal power source SD_VDD having a level different from a level of the external power source T_VDD. The forwarding lock signal LKF may be understood to correspond to LKIN in FIG. 2. The transfer lock signal LK1 may be understood to correspond to LKOUT in FIG. 2.

More specifically, the display driving circuit 20 may include an input circuit 30, a clock data recovery circuit (hereinafter referred to as a "CDR") 40, a comparison unit 50 and an output circuit 32.

The input circuit 30 is for receiving a forwarding lock signal LKIN through the lock signal transmission line 12 to which the external power source VDD is applied. The input circuit 30 may be configured to transfer the forwarding lock signal LKIN to the comparison unit 50 through the internal input pull-up circuit using the internal power source SD_VDD having a level different from a level of the external power source T_VDD. In this case, the internal input pull-up circuit may be understood to include a pull-up device Q1 and a pull-up resistor R1. A detailed construction and operation of the internal input pull-up circuit are described later.

The CDR 40 is configured to recover data and a clock from display data and to provide an internal lock signal iLK obtained by determining whether the clock has been recovered normally.

The comparison unit 50 is configured to output a comparison signal obtained by comparing the forwarding lock signal LKIN transferred through the input circuit 30 and the internal lock signal iLK of the CDR 40 that has determined a state of an internal recovery clock. In this case, the comparison unit 50 may be configured to include a NAND gate that operates the forwarding lock signal LKIN and the internal lock signal iLK. The NAND gate may be configured to output a comparison signal corresponding to a result of

the logical NAND operation of the forwarding lock signal LKIN and the internal lock signal iLK.

The output circuit 32 may be configured to generate a transfer lock signal LKOUT having a level corresponding to a level of the comparison signal of the comparison unit 50 and to output the transfer lock signal LKOUT. The transfer lock signal LKOUT of the output circuit 32 may be understood to correspond to the transfer lock signal LK1 in FIG. 1.

In the construction, the input circuit 30, the CDR 40 and the output circuit 32 are illustrated as being operated using the internal power source SD_VDD. The comparison unit 50 may also be understood as being operated using the internal power source SD_VDD.

Furthermore, the input circuit 30 may be understood to include an internal input pull-up circuit as described above. Although not specified in the drawing, the internal input pull-up circuit may be understood to be configured to include the pull-up device Q1 and the pull-up resistor R1.

In this case, the pull-up device Q1 may be composed of an NMOS transistor, and may maintain turn-on by the internal power source SD_VDD applied to a gate thereof. Furthermore, the pull-up device Q1 may be understood to receive the forwarding lock signal LKIN through the lock signal transmission line 12 and to form an open drain for the reception of the forwarding lock signal LKIN.

The pull-up resistor R1 is configured to transfer, to the comparison unit 50, the forwarding lock signal LKIN received through the pull-up device Q1. The pull-up resistor R1 may be configured between the gate and source of the pull-up device Q1 composed of the NMOS transistor.

By the construction of the input circuit 30, the forwarding lock signal LKIN may be transferred to the comparison unit 50 through a node between the source of the pull-up device Q1 and the pull-up resistor R1.

The output circuit 32 may be understood to include an internal output pull-up circuit as described above. Although not specified in the drawing, the internal output pull-up circuit may be understood to be configured to include a switching device Q2 and a protection circuit Q3.

In this case, the switching device Q2 may be composed of an NMOS transistor, and may be configured to be switched based on a level of the comparison signal of the comparison unit 50 applied to a gate thereof. Furthermore, the protection circuit Q3 may be composed of an NMOS transistor, and may be configured to maintain turn-on by the internal power source SD_VDD applied to a gate thereof.

By the construction of the output circuit 32, the transfer lock signal LKOUT may be outputted through the protection circuit Q3 in response to a switching state of the switching device Q2. At this time, the NMOS transistor of the protection circuit Q3 may be understood to form an open drain for the output of the transfer lock signal LKOUT.

When the forwarding lock signal LKIN to which the external power source T_VDD has been applied is inputted to the display driving circuit 20 constructed as in FIG. 2, the forwarding lock signal LKIN is applied to the pull-up resistor R1 of the input circuit 30 having an open drain through the pull-up device Q1. The pull-up resistor R1 may transfer, to the comparison unit 50, the forwarding lock signal LKIN biased by the internal power source SD_VDD.

As described above, a voltage difference between heterogeneous voltages may be buffered by an operation of the input circuit 30. Compatibility for sharing a lock signal between the timing controller 10 and the display driving circuit 20 using heterogeneous voltages may be secured.

If the aspect of FIG. 2 is used as the display driving circuit 22, it may be understood that internal power sources between adjacent display driving circuits and the display driving circuit 22 do not substantially have a difference. Accordingly, if the display driving circuits 20, 22 and 24 transfer the transfer lock signals LK1, LK2 and LKn by using the cascade method, a transfer lock signal may be easily shared between adjacent display driving circuits.

Furthermore, the display driving circuit 24 may solve a compatibility problem, attributable to an environment in which heterogeneous voltages are used, by outputting the feedback lock signal LKL through the internal output pull-up circuit using the internal power source SD_VDD having a level different from a level of the external power source T_VDD.

If the aspect of FIG. 2 is used as the display driving circuit 24, the feedback lock signal LKL may be understood to correspond to LKOUT in FIG. 2, and the transfer lock signal LKn may be understood to correspond to LKIN in FIG. 2.

It has been described with reference to FIG. 2 that the output circuit 32 includes the internal output pull-up circuit including the switching device Q2 and the protection circuit Q3.

In the internal output pull-up circuit, the switching device Q2 may be configured to be switched based on a level of the comparison signal of the comparison unit 50 applied to the gate thereof. The protection circuit Q3 may be configured to maintain turn-on by the internal power source SD_VDD applied to the gate thereof.

The protection circuit Q3 constructed using the NMOS transistor forms an open drain to output the feedback lock signal LKL.

Accordingly, the feedback lock signal LKOUT of the lock signal transmission line 14 may be driven by the switching of the switching device Q2. Since the external power source T_VDD has been applied to the lock signal transmission line 14, the timing controller 10 may receive the feedback lock signal LKL driven by the external power source T_VDD.

As described above, a voltage difference between heterogeneous voltages may be buffered by an operation of the output circuit 32. Compatibility for sharing a lock signal between the timing controller 10 and the display driving circuit 24 using heterogeneous voltages may be secured.

Accordingly, the present disclosure may buffer a voltage difference between heterogeneous power sources of the timing controller and the display driving circuit by the pull-up of the input circuit or the output circuit, and may secure compatibility for sharing a lock signal in an environment in which heterogeneous power sources are used.

It will be apparent to those skilled in the art that various modifications and variations can be made in the display apparatus having a lock function and the display driving circuits of the present disclosure without departing from the spirit or scope of the aspects of the present disclosure. Thus, it is intended that the present disclosure covers the modifications and variations of the aspects provided they come within the scope of the appended claims and their equivalents.

What is claimed is:

1. A display driving circuit having a lock function, comprising:

a comparison unit configured to receive a transfer lock signal and output a comparison signal obtained by comparing the transfer lock signal and an internal lock signal obtained by determining a state of an internal recovery clock; and

an output circuit configured to generate a feedback lock signal having a level corresponding to a level of the comparison signal to output the feedback lock signal to a lock signal transmission line to which a first power source is applied.

2. The display driving circuit of claim 1, wherein the output circuit includes an internal output pull-up circuit configured to transfer the feedback lock signal to the lock signal transmission line by using a second power source having a level different from a level of the first power source.

3. The display driving circuit of claim 2, wherein the internal output pull-up circuit comprises:

a switching device configured to receive the comparison signal and output the feedback lock signal by being switched based on the level of the comparison signal; and

a protection circuit configured to maintain turn-on for a connection between the lock signal transmission line and the switching device by the second power source.

4. The display driving circuit of claim 3, wherein the switching device comprises a first NMOS transistor having a gate to which the comparison signal is applied, the protection circuit comprises a second NMOS transistor having a gate to which the second power source is applied, and

the second NMOS transistor is configured between a drain of the first NMOS transistor and the lock signal transmission line and forms an open drain for the lock signal transmission line.

5. The display driving circuit of claim 1, wherein the comparison unit comprises a NAND gate configured to operate the transfer lock signal and the internal lock signal, and

the NAND gate outputs the comparison signal.

6. A display driving circuit having a lock function, comprising:

an input circuit configured to receive a forwarding lock signal through a lock signal transmission line to which a first power source is applied and to transfer the forwarding lock signal;

a comparison unit configured to output a comparison signal obtained by comparing the forwarding lock signal transferred through the input circuit and an internal lock signal obtained by determining a state of an internal recovery clock; and

an output circuit configured to generate a transfer lock signal having a level corresponding to a level of the comparison signal and output the transfer lock signal.

7. The display driving circuit of claim 6, wherein the input circuit includes an internal input pull-up circuit configured to transfer the forwarding lock signal to the comparison unit by using a second power source having a level different from a level of the first power source.

8. The display driving circuit of claim 7, wherein the internal input pull-up circuit comprises:

a pull-up device configured to maintain turn-on by the second power source and receive the forwarding lock signal through the lock signal transmission line; and

a pull-up resistor configured to transfer the forwarding lock signal received through the pull-up device, and provides the comparison unit with the forwarding lock signal applied to the pull-up resistor.

9. The display driving circuit of claim 8, wherein the pull-up device comprises a first NMOS transistor having a gate to which the second power source is applied,

9

the pull-up resistor is configured between the gate and source of the first NMOS transistor, and the forwarding lock signal is transferred to the comparison unit through a node between a source of the pull-up device and the pull-up resistor.

10. The display driving circuit of claim 7, wherein: the output circuit comprises an internal output pull-up circuit, the internal output pull-up circuit comprises:

a switching device configured to receive the comparison signal and switched based on the level of the comparison signal; and

a protection circuit configured to maintain turn-on by the second power source, and

the transfer lock signal is outputted through the protection circuit in response to a switching state of the switching device.

11. The display driving circuit of claim 10, wherein: the protection circuit comprises a second NMOS transistor having a gate to which the second power source is applied, and

the second NMOS transistor forms an open drain for output of the transfer lock signal.

12. The display driving circuit of claim 6, wherein: the comparison unit comprises a NAND gate configured to operate the forwarding lock signal and the internal lock signal, and

the NAND gate outputs the comparison signal.

13. A display apparatus having a lock function, comprising:

a timing controller configured to output a forwarding lock signal through a first lock signal transmission line and receive a feedback lock signal through a second lock signal transmission line; and

a plurality of display driving circuits comprising a first display driving circuit configured to receive the forwarding lock signal through the first lock signal transmission line and output a transfer lock signal and a second display driving circuit configured to receive the transfer lock signal through a third lock signal transmission line and output the feedback lock signal through the second lock signal transmission line, wherein a first power source is applied to the first lock signal transmission line and the second lock signal transmission line.

14. The display apparatus of claim 13, wherein the first and second display driving circuits use a second power source having a level different from a level of the first power source,

the first display driving circuit receives the forwarding lock signal through a first internal input pull-up circuit using the second power source, and

the second display driving circuit outputs the feedback lock signal through a second internal output pull-up circuit using the second power source.

15. The display apparatus of claim 13, wherein: the first and second display driving circuits use a second power source having a level different from a level of the first power source, and

the first display driving circuit comprises: an input circuit configured to receive the forwarding lock signal through the first lock signal transmission line; a comparison unit configured to output a comparison signal obtained by comparing the forwarding lock signal transferred through the input circuit and an internal lock signal obtained by determining a state of an internal recovery clock; and

10

an output circuit configured to generate the transfer lock signal having a level corresponding to a level of the comparison signal and output the transfer lock signal, and

5 wherein the input circuit transfers the forwarding lock signal to the comparison unit through the internal input pull-up circuit using the second power source.

16. The display apparatus of claim 15, wherein: the input circuit comprises the internal input pull-up circuit, and

the internal input pull-up circuit comprises:

a pull-up device configured to maintain turn-on by the second power source and receive the forwarding lock signal through the first lock signal transmission line; and

a pull-up resistor configured to transfer the forwarding lock signal received through the pull-up device, and provides the comparison unit with the forwarding lock signal applied to the pull-up resistor.

17. The display apparatus of claim 16, wherein: the pull-up device comprises a first NMOS transistor having a gate to which the second power source is applied,

the pull-up resistor is configured between the gate and source of the first NMOS transistor, and the forwarding lock signal is transferred to the comparison unit through a node between a source of the pull-up device and the pull-up resistor.

18. The display apparatus of claim 13, wherein: the first and second display driving circuits use a second power source having a level different from a level of the first power source, and

the second display driving circuit comprises: a comparison unit configured to receive the transfer lock signal and output a comparison signal obtained by comparing the transfer lock signal and an internal lock signal obtained by determining a state of an internal recovery clock; and

an output circuit configured to generate the feedback lock signal having a level corresponding to a level of the comparison signal and output the feedback lock signal to the second lock signal transmission line, and

the output circuit transfers the feedback lock signal to the second lock signal transmission line through the internal output pull-up circuit using the second power source.

19. The display apparatus of claim 18, wherein: the output circuit comprises the internal output pull-up circuit, and

the internal output pull-up circuit comprises:

a switching device configured to receive the comparison signal and switched based on the level of the comparison signal; and

a protection circuit configured to maintain turn-on for a connection between the second lock signal transmission line and the switching device by the second power source.

20. The display apparatus of claim 19, wherein: the switching device comprises a first NMOS transistor having a gate to which the comparison signal is applied,

the protection circuit comprises a second NMOS transistor having a gate to which the second power source is applied, and

the second NMOS transistor is configured between a drain of the first NMOS transistor and the second lock signal
